UNITED STATES PATENT OFFICE.

COKE COTHAM, OF MONTICELLO, ARKANSAS.

HAY-PRESS.

No. 805,414.

Specification of Letters Patent.

Patented Nov. 21, 1905.

Application filed December 2, 1904. Serial No. 235,188.

To all whom it may concern:

Be it known that I, COKE COTHAM, a citizen of the United States, and a resident of Monticello, in the county of Drew and State of Arkansas, have invented a new and Improved Hay-Press, of which the following is a specification.

This invention relates to presses of the toggle-plunger type, and has for its object not only to provide a press of this character having new and improved means whereby the plunger may be operated, but also to simplify and improve the press-box, feed-door construction, and frame.

5 The invention consists of the special construction, arrangement, and combination of parts hereinafter fully described, illustrated in the accompanying drawings, and pointed out in the claims.

10 In the drawings, Figure 1 is a top plan view illustrating my invention, and Fig. 2 is a side elevation.

In the practice of my invention I employ a press-box A, having any suitable door at its discharge end, and a feed-door B, held closing the feed-opening by a suitable catch C, under tension of springs D. The topside E of the press-box is made yielding from its forward end rearwardly and adapted to be forced down to choking position of the hay being pressed by a suitable stirrup consisting of arms F, pivotally secured at their lower ends, and a rod G, arranged above the rear end of the press-box and connecting the upper ends of the arms 15 F. By means of the stirrup just described it is apparent that by forward adjustment of its free end the rear end of the press-box top will be forced down to choking position of hay being pressed. The forward end of the 20 press-box is left open, adapted to receive a follower H. (Indicated by dotted lines in the figures of the drawings.) The press-box is provided with a suitable frame and support, whose lower members may be in the form of 25 runners I, and with standards J K, adapted for the purpose as will appear in the following description.

To the upper end of the standard K, I 30 hingedly secure the inner end of a lever L. The follower H is connected with the standard K by means of a suitable toggle M, substantially as shown in Fig. 1. N denotes an arm with its lower end secured to the toggle M and its upper end pivotally secured to the forward end of an arm O, whose rear end is hinged to the upper end of the standard J.

The lever L is connected with the forward end of the arm O and the upper end of the arm N by rods P P, substantially as shown in Fig. 2.

It is intended that the catch C be in the nature of a suitable spring device adapted to be drawn back from locking position of the door B by a string Q, extending therefrom, and with its other end secured to the lower end of the arm N or at the connection R in the toggle M, as may be desired.

The construction of my improved press will be understood from the above description.

In the use of my improved press, the lever L, toggle M, and arms N O being adjusted as indicated by dotted lines in Fig. 2 and the follower thereby drawn forward, as is also indicated by dotted lines in this view, it is apparent that through connection of the string Q, as above described, the latch will be drawn back from locking position of the door B, when the latter, by tension of the springs D, will be pulled to open position. (Indicated by dotted lines in Fig. 1.) The stirrup at the discharge end of the press-box is now adjusted, as indicated by dotted lines, and thereby forcing down the presser-box top to the choking position hereinbefore described. With the posts at adjusted position hay may be fed into the press-box in rear of the follower H, the door 85 being closed and locked, as stated. Obviously upon pulling down of the free end of the lever L the follower H will be forced, through means of its connections with the lever L, to compressing action of the hay in the 90 press-box.

Having thus described my invention, what I claim as new, and desire to secure by Letters Patent, is—

1. The combination of the press-box, its frame employing suitable standards, a follower in the press-box, a toggle connecting the follower with said frame, an operating-lever, arms hingedly connected together and with their ends secured respectively to the operating-lever and one said standard, an arm extending from the hingedly-connected arms to the toggle, and a door to the press-box held closed by a suitable locking device and under opening tension, substantially as described.

2. The combination of the press-box, its frame employing suitable standards, a follower in the press-box, a toggle-lever connecting the follower with said frame, an operating-lever, arms hingedly connected together and with their ends secured respectively to the operating-lever and one said standard, an arm ex-

tending from the hingedly-connected arms to the toggle, a door to the press-box held closed by a suitable catch device, springs operating to draw the door open, and means whereby the catch is drawn from holding position of the door, through operation of the follower-connecting devices, upon raising action of the operating-lever, substantially as described.

10 3. The combination with a press-box having a suitable feed-opening, of a follower and operating-levers, a door for closing the feed-opening, the door being hingedly supported at one edge adapted to swing upwardly to open

position, a coil-spring extending across the hinge edge of the door having one end secured thereto, and its other end secured to the press-box at a location placing the spring under tension, a fixedly-located yielding catch adapted for holding the door closed, and means whereby the catch is drawn from holding positions of the door, through action of the follower-operating levers, substantially as described. 15 20

COKE COTHAM.
